(57) CLAIM

The ornamental design for a jacket for a portable speaker, as shown and described.

DESCRIPTION

FIG. 1 is a top, front and side perspective view of a jacket for a portable speaker embodying my new design.

FIG. 2 is a front view thereof.

FIG. 3 is a back view thereof.

FIG. 4 is a first side view thereof.

FIG. 5 is a second side view thereof.

FIG. 6 is a top view thereof.

FIG. 7 is a bottom view thereof.

FIG. 8 is a bottom, front and side perspective view thereof; and,

FIG. 9 is a top, front and side perspective view thereof, shown in environmental use.

Broken lines are used to illustrate features of the jacket for a portable speaker which form no part of the claimed design. In FIG. 9, the jacket is shown surrounding a portable speaker shown to represent environment which forms no part of the claimed design.
